DIRECTIONAL ANTENNA SYSTEM

Application filed October 19, 1927, Serial No. 227,129, and in France November 4, 1926.

The present invention relates to directional antenna systems for both transmission and reception and which may be applied also to radio-goniometers and revolving radio-beacons.

The use in connection with radio-electric transmission and reception work of simple loops or frame antennæ consisting of coils possessing reduced thickness compared with their diameter, or, more generally, with their section, is quite well known. It is stated that such a loop or frame antenna combined with detector devices, amplifiers and recorders of well-known kind or with known transmitter apparatus, receives or sends out with a maximum effect such electric waves as come from or are travelling in the directions coinciding with their plane, while such signals as come from or are travelling in directions located at right angles thereto exhibit minimum strength.

Now, the present invention has as its principal object to provide an antenna system having complex frames or loops adapted to insure sharper directional effects than that obtainable heretofore with simple frame or coil antennæ of the kind above referred to.

According to one embodiment of the basic idea of this invention, the present invention comprises an assembly of simple, vertical, parallel frame or coil antennæ so that their vertical diameters come to be in the same plane and are equally spaced. These frame antennæ are united with one another by connections such that the assembly forms a single circuit, two successive frame antennæ being in series or in opposition (differential connection). The assembly is connected in the well-known way with transmitter or receiver apparatus. The surfaces of the turns, their number and the shapes of the different loop antennæ may be chosen at will. A better understanding of the invention will be had from the following description thereof, and therefrom when read in connection with the attached drawings throughout which like reference characters indicate like parts, and in which, Figure 1 shows one embodiment of the present invention, while Figures 2 to 8 in-

clusive show modifications of the arrangement of Figure 1.

A detailed description of the invention will now be given with reference to the drawings, and in particular to Figures 1 and 2 thereof, which show, by way of example, two embodiments of the idea underlying the present invention. Instead of being arranged in a single circuit, the frame or loop antennæ could also be disposed in several circuits connected separately with the transmission or receiving apparatus.

One particular embodiment of the present invention is illustrated in Fig. 1 which discloses an antenna system comprising $(n+1)$ simple frames or loops, the total surfaces (areas) (sum total of the surfaces of the turns of each simple frame) of the successive frame antenna being proportional to the following numbers:

$$1, \frac{n}{1}, \frac{n(n-1)}{2}, \frac{n(n-1)}{2}, \dots, \frac{(n-p+1)}{p}, \dots, \frac{n}{1}, 1$$

all of the frames being mounted in the same vertical plane, and two adjacent or successive frames being connected in opposition so that they are traversed by the current in opposite directions. As hereinbefore pointed out, the simple frame or coil antennæ may be assembled either to form a single circuit consisting of a single complex coil or else several circuits connected separately with the transmitter or receiver apparatus. In this case, the transmission or the reception, as the case may be, is of maximum value in the directions located in or coinciding with the plane of the frames, and of zero value in the directions perpendicular thereto. The directional effect will be so much more accentuated, the greater the number of simple frame antenna and it is substantially independent of the distance and the space separating the simple frames.

Another special embodiment of the basic idea of the present invention is illustrated in Fig. 2 which discloses an antenna system comprising $(n+1)$ simple frames or loops,

with the total surfaces of successive frames being proportional to the following figures:

$$5 \quad 1, \frac{n}{1}, \frac{n(n-1)}{2} \dots \frac{n(n-1)}{2} \dots \frac{(n-p+1)}{p} \dots \frac{n}{1}, 1$$

all of the frames being perpendicular to the vertical plane containing their diameters, and two adjacent or successive frames being connected in series, so that the current is 10 caused to flow through all of the frames in the same direction. As hereinbefore explained, the constituent simple frames may be assembled either to form a single circuit comprising one complex frame (Figure 2) or 15 else several circuits connected separately with the transmitter or receiver apparatus.

A modification of the second embodiment here considered comprises as shown in Figs. 3 to 8, inclusive, a system of $(n+1)$ groups 20 of vertical antennæ disposed in the same plane and at equal distance, each group comprising:

(a) either a single antenna, the effective heights being successively for the different 25 antennæ:

$$1, \frac{n}{1}, \frac{n(n-1)}{2} \dots \frac{n(n-1)}{2} \dots \frac{(n-p+1)}{p} \dots \frac{n}{1}, 1$$

(b) or m identical antennæ, the values of 30 m being for the different groups proportional to:

$$1, \frac{n}{1}, \frac{n(n-1)}{2} \dots \frac{n(n-1)}{2} \dots \frac{(n-p+1)}{p} \dots \frac{n}{1}, 1$$

(c) or else any desired number of antennæ provided that, for each group, the sum total of effective antenna heights is proportional 35 to:

$$40 \quad 1, \frac{n}{1}, \frac{n(n-1)}{2} \dots \frac{n(n-1)}{2} \dots \frac{(n-p+1)}{p} \dots \frac{n}{1}, 1$$

All of the antennæ comprised in one and the same group are in phase, while those 45 of two adjacent or successive groups are phase-displaced by 180 degrees.

In case each group comprises only one antennæ, a phase displacement angle of 180 degrees between successive groups may be insured, if n is an odd number, by uniting the antennæ in a single frame by transverse connections. Figures 3 and 4 show by way of example arrangements of such antennæ in the case where $n=3$ and where $n=5$, respectively, and in which the system comprises simple antennæ indicated by vertical lines, the lengths of said antennæ being proportional to the numbers 1, 3, 3, 1 (in the case of Figure 3), and to the numbers 1, 5, 10, 10, 5, 1 (in the case of Figure 4) transverse connections are indicated in Figures 3 and 4 by fine lines.

In cases where each group is constituted by m identical antennæ, m having values as indicated above, the phase displacement angle 65 of 180 degrees between successive groups may

also be obtained by arranging or combining all of the antennæ in a single frame or loop. The number of the antennæ of the even groups is equal to that of the odd groups. Figures 5, 6, 7 and 8 show embodiments by 70 way of example for $n=1, 2, 3, 4$.

Instead of being disposed in a single frame, the different antennæ could also be distributed in several frames in various other ways which will be obvious. 75

The invention comprises also the construction of rotating radio-goniometers and radio-beacons by turning about a vertical axis the complex coils or assemblies of complex coils of the kind as hereinbefore disclosed. 80

Having thus described my invention, I claim:

1. A directional antenna system for use in wireless signalling comprising $(n+1)$ groups of antenna where $n=2$ or more, the 85 sums of the effective heights of successive antenna groups being proportional to the numbers of the series:

$$1, \frac{n}{1}, \frac{n(n-1)}{2} \dots \frac{n}{1}, 1. \quad 90$$

2. A directional antenna system for use in wireless signalling comprising a plurality of groups of antennæ, each group comprising a plurality of elementary identical antenna whose numbers are proportional to the numbers of the series: 95

$$1, \frac{n}{1}, \frac{n(n-1)}{2} \dots \frac{n}{1}, 1. \quad 100$$

where $n+1$ is the number of groups of antennæ and n equals at least 2.

3. A directional antenna system for use in wireless signalling comprising a plurality of groups of antennæ connected together to form a circuit, each group comprising a plurality of elementary identical interconnected antenna whose numbers are proportional to the numbers of the series: 105

$$1, \frac{n}{1}, \frac{n(n-1)}{2} \dots \frac{n}{1}, 1. \quad 110$$

where $n+1$ is the number of groups of antennæ and n is at least 2. 115

4. A directional system of antennæ, comprising $n+1$ units, n standing for at least 2, whose effective height varies according to the series: 120

$$1, \frac{n}{1}, \frac{n(n-1)}{2} \dots \frac{n}{1}, 1,$$

each unit comprising at least one vertical antenna whose lower and upper extremities are conductively connected with the corresponding extremities of the vertical antennæ belonging to other units of the system thereby forming a closed circuit. 125

5. A directional system of antennæ, comprising $n+1$ units, n standing for at least 2, 130

whose effective height varies according to the series:

$$1, \frac{n}{1}, \frac{n(n-1)}{2}, \dots, \frac{n}{1}, 1,$$

5 each unit comprising a plurality of elementary antennæ at least one of which is connected at its lower end to the lower end of a corresponding antenna in another unit.

10 6. A directional system of antennæ, comprising $n+1$ groups of identical vertical antennæ in which n stands for at least 2, the numbers of these antennæ in each group varying according to the series:

$$15 1, \frac{n}{1}, \frac{n(n-1)}{2}, \dots, \frac{n}{1}, 1,$$

the lower and upper extremities of each antenna being conductively connected to the 20 corresponding extremities of the vertical antennæ belonging to adjacent groups, thereby forming a closed circuit in which the exciting phase difference of the adjacent groups has the value of 180° .
